UNITED STATES PATENT OFFICE.

WILLIAM MAIN, OF BROOKLYN, NEW YORK.

INCANDESCENT ELECTRIC LAMP.

SPECIFICATION forming part of Letters Patent No. 336,729, dated February 23, 1886.

Application filed July 30, 1885. Serial No. 173,010. (No model.)

To all whom it may concern:

Be it known that I, WILLIAM MAIN, a citizen of the United States, residing in Brooklyn, in the county of Kings and State of New York, 5 have invented certain new and useful Improvements in Incandescent Electric Lamps, of which the following is a description in such full, clear, concise, and exact terms as to enable any one skilled in the art or arts to which 10 my invention belongs to make and use the same, reference being had to the accompanying drawings, making part of this specification, and to the letters and figures of reference marked thereon.

15 My invention consists of a novel form of incandescent electric lamp having a metal base, and the means for illuminating and extinguishing the same.

Reference being had to the drawings making part of this specification, Figure 1 is a longitudinal cross-section through my improved lamp. Fig. 2 is an elevation of the lamp-switch, by means of which the current is turned in and out of the lamp, for the purpose of 25 illuminating and extinguishing the same. Figs. 3 and 4 are top and bottom views of detail parts of said switch. Fig. 5 is a top view of a section through the lamp on the dotted line *xy*, Fig. 1; and Fig. 6 illustrates one means 30 of exhausting the lamp-chamber.

I take a cylindrical piece of metal, *a*, formed as shown in the drawings, and on the lower side of the perforated partition in said cylinder I place the insulating-ring *f*. The flanged metal tube *b* is then slipped in place, and held in position, if desirable, by the perforated cap *c*. The upper end of the pipe *b* is screw-threaded to receive the metal nut *d*, which has inclined sides to correspond with the sides of 40 the cavity in the top of the cylindrical piece *a*. Before the nut *d* is screwed on the tube *b* a disk of suitable insulating material is placed between the said nut and its seat in the cylindrical piece *a*. These disks *e* and *f* may be 45 made of mica, although I do not confine myself to the use of this single material. The interstices between the nut *d*, cylindrical piece *a*, pipe *b*, and ring *c* are filled with any suitable insulating and sealing material before 50 the nut is screwed down home.

It will be observed that the hole in the par-

tition of the cylindrical piece *a* is large enough to allow the pipe *b* to pass through without touching, and that the tapering nut *d* centers the pipe *b*, so that it does not come in contact 55 with the cylindrical piece *a* or the flanged ring *c*, and is completely insulated therefrom.

In connection with the disks *e* and *f*, for the purpose of insulating and hermetically sealing the said parts, I prefer to use a plastic cement, 60 which is set either by chemical action or by the assistance of heat. The nut *d* is screwed home while this insulating and sealing material is in a plastic state, thereby packing it tightly in all the said interstices and squeezing 65 out the surplus material. The ring *c* may or may not be employed; but I prefer to use it. After the insulating material has been introduced and the nut screwed home I invert the 70 whole and pour insulating and sealing material around the flange on the pipe *b*, and then screw down the flanged ring *c*, removing any surplus material that is squeezed out about the pipe *b*. The standards supporting the 75 illuminating-conductor of the lamp are then inserted, respectively, in the cylindrical piece *a* and the nut *d*, and are preferably formed of stiff wire *j j'*, to which the illuminating-filament may be directly attached, or by means of intermediate platinum wires, *k k*. So 80 I next prepare a spun-metal cup *g g*, substantially of the form shown in the drawings, which snugly fits the cylindrical piece *a*, and which in its outer fold embraces the lower end of the glass illuminating-chamber of the lamp 85 hermetically sealed therein. By forming the spun-metal cup as shown a free circulation of air is admitted to both sides of that portion of the said cup which contains the bottom of the glass chamber *i i*, thereby tending to keep 90 the same cool and preserve the joint air-tight. Again, any heat conducted to the base *a b c d*, before reaching said joint, is made to pass over a considerable radiating surface and is thus diminished. This form of cup also forms an 95 elastic support for the glass chamber *i i*, which considerably diminishes the liability of said chamber to crack or tear away from the sealing material in which it is bedded.

To exhaust the lamp-chamber, a soft-metal 100 pipe, *h*, Fig. 6, is soldered into the lower end of the pipe *b*, which pipe *h* is connected

to any suitable exhaust-pump. This pipe may be made of lead or other suitable material, so that when the chamber has been exhausted the pipe may be pinched and worked 5 together to completely close the bore thereof, and then cut off and formed into a small projecting teat. (See Fig. 1.) As an extra precaution against leakage, solder may also be applied.

10 The switch by means of which the electrical current is turned in and out of the lamp is formed as follows: A base, *m*, made of insulating material—such as gutta percha or wood—is fitted with the binding-posts *n* *n'*, one of 15 which is electrically connected with the rod *r*, spring *u*, and contact-rod *r'*, said contact-rod *r'* playing longitudinally in the bore of the cylinder *m*. (See Fig. 1.) The binding-post *n* is electrically connected to the incline 20 plates *q q q* by means of the wires *o*. The cylinder *m*, Fig. 2, is provided with a series of short inclines, *p q p q*, &c., the inclines *q* being faced with metal and electrically connected to the binding-post *n*, and the inclines *p* 25 being formed from the insulating material composing the said cylinder. Revolving on a shoulder above the said inclines is the metal disk *z*, provided with the flat metal springs *t*, which ride up and down the inclines when 30 the disk is turned with a right-hand revolution about its axis. A metal flange-ring, *v*, screws down upon the disk *z*, which holds the disk in place, but does not interfere with its revolution. This metal flange-ring has also 35 an external screw-thread, by means of which it is screwed in the lower end of the cylindrical piece, *a*, the teat formed on the end of the tube *b* forming electrical connection with the spring-rod *r'*, as shown in Fig. 1 of the drawings. It is obvious that by the revolution of 40 the disk *z*, the circumference of which should be suitably milled, the current is turned in and out of the lamp as the springs *t* make contact alternately with the inclines *p p p* 45 and *q q q*. My purpose of employing more than one incline *q* is to diminish the sparking at these contacts, and also by providing more than one path for the current to guard against a failure in operation if a good contact should not be made at either of said 50 points.

The form of switch which I have here described is more compact and simple than any other efficient switch of which I have any 55 knowledge. Instead of making the disk holding the springs the revolving part of the switch, I may, of course, make this stationary, and the part containing the inclines adapted to revolve.

60 The course of the current through the lamp is, therefore, as follows: From the generator to binding-post *n*, conductor *o*, inclines *q*, springs *t*, disk *z*, ring *v*, cylindrical piece *a*, support *j*, illuminating-conductor, support *j'*, nut *d*, tube *b*, spring-rod *r' u r*, binding-post *n'*, back to generator.

When it is desired to unseal the lamp-chamber to replace the illuminating-conductor, or for any other purpose, heat may be applied to the lower rim of the spun cup *g*, melting 75 the solder, and permitting the cup to be removed from the base without interfering with the sealing contained therein.

To re-exhaust the lamp-chamber after the last-mentioned joint has been sealed, the projecting teat and plug may be withdrawn from the end of the tube *b*, and pipe leading from the exhaust-pump inserted, and the lamp exhausted and sealed, as hereinbefore described.

Having described my invention, I claim and desire to secure by Letters Patent—

1. In an incandescent electric lamp, a revolving disk set upon the axis of the lamp and intervening between the bottom of the lamp and the holder thereof, said disk being provided with suitable contacts and insulating section coacting in the circuit, said disk rotating independently of the lamp and the holder thereof, by which the current is turned in or out of the lamp by the rotation 85 of said disk about its own axis and the axis of the lamp, substantially as described.

2. In an incandescent electric lamp, a switch for turning the current in and out of the lamp-circuit, consisting of a disk set upon the axis 95 of the lamp and made to rotate continually in one direction about its own axis and the axis of the lamp, the lamp and holder remaining stationary, said disk being fitted with the necessary contact and insulating points or sections, substantially as described.

3. In an incandescent electric lamp and forming the illuminating-chamber thereof, the combination of a transparent globe and a metal base consisting of a double convoluted cup, one 105 of which convolutions supports the illuminating-chamber, and the other furnishes an air and radiating chamber around the base of the lamp, substantially as described.

4. A metal base to support the glass chamber of an incandescent electric lamp, consisting of a tube-section having a double convolute spun about it, permitting the metal walls that embrace each side of the glass chamber to expand independently of said tube, substantially 115 as described.

5. A metal base of the illuminating-chamber of an incandescent electric lamp, consisting of the combination of a cup, *g*, cylindrical piece *a*, flanged pipe *b*, and nut *d*, all being connected and combined substantially as described.

6. An electric switch consisting of the combination of a spring contact-rod, *r u r'*, connected with one binding-post, and a revolving metallic disk, *z*, provided with metal springs *t*, and a series of inclines, *p q*, suitably provided with contacts connected with the other binding-post, substantially as described.
